MEANS FOR DESIGN COLORING OF FABRIC WEBS

George P. Feindel, Rock Hill, S. C., assignor to Rock Hill Printing & Finishing Company, a corporation of Delaware

Application September 2, 1953, Serial No. 378,028

1 Claim. (Cl. 118—44)

This invention relates to the coloring of fabric webs, and more particularly to an apparatus by which unique design coloring effects may be applied to fabric webs and to the manner in which this apparatus is used.

Briefly described, the apparatus of the present invention is characterized by a color applicator roll having an intaglio pattern of spaced design elements formed in the peripheral surface thereof and from which peripheral surface color is transferred to a fabric web exclusive of the intaglio design elements. By this arrangement, when the fabric web is caused to travel continuously over a backing surface moving with the web and the applicator roll is disposed to run against the web in opposed relation to the backing surface, the result is to form a design on the web by the absence of color. That is, color is applied to the web from the peripheral surface of the applicator roll except at the intaglio design elements, so that the form of these design elements appears on the web outlined by the color applied from the applicator roll to produce striking and unusual design effects.

The present invention is described in further detail below in connection with the accompanying drawings, in which:

Fig. 1 is a side elevation, in more or less schematic form, of representative apparatus embodying the present invention;

Fig. 2 is a perspective detail illustrating further the form and arrangement of the color applicator roll;

Fig. 3 is an exaggerated partly sectioned detail in side elevation, corresponding to Fig. 1, in which the treatment of the fabric web is illustrated as it passes through the apparatus shown in Fig. 1; and

Fig. 4 is an enlarged fragmentary plan view of the exposed face of the fabric web as shown in section leaving the apparatus in Fig. 3.

Referring now in detail to the drawings, and more particularly at first to Fig. 1, the embodiment of the present invention shown for purposes of illustration comprises an embossing press arranged in all respects like the apparatus disclosed in copending application Serial No. 293,820, filed June 16, 1952, now U. S. Patent No. 2,667,426, except for the form of the color applicator roll 10.

Fig. 1 shows an embossing press in which a supply roll R is arranged for delivery of a fabric web W through tensioning bars as at 12 and between a top steel engraved embossing roll 14 and a bottom composition or filled impression roll 16, such as are conventionally provided in embossing presses, the embossing and impression rolls 14 and 16 being geared together and driven as disclosed in the above noted copending application, and the embossed fabric web being trained over a portion of the peripheral surface of the impression roll 16 past the color applicator roll 10 before leaving the apparatus, as at W', as directed by a guide roll 18.

The above described embossing press has been selected as a matter of convenience in representing an embodiment of the present invention because the design effects produced according to this invention appear particularly well

2

on embossed fabrics, as is noted further below. However, the primary function of the embossing roll 14 and impression roll 16 is as means for causing continuous travel of the fabric web W and for presenting a backing surface moving with the web W in relation to which the applicator roll 10 can be disposed. For this purpose, the embossing roll 14 and impression roll 16 might be alternatively arranged as disclosed in copending application Serial No. 376,712, filed August 26, 1953, or replaced by a smooth surfaced backing roll and opposed pressure used simply as a pair of draw rolls or as disclosed in copending application Serial No. 376,704, filed August 26, 1953.

In order to dispose the applicator roll 10 as shown in Fig. 1, a mounting bracket 20 is provided on the embossing press frame structure, and this mounting bracket 20 is fitted with pressure adjusting screws 22 by which the applicator roll 10 may be set in proper color applying relation to the impression roll 16. It should also be noted that the applicator roll 10 is positively rotated in relation to the speed of the impression roll 16 by a suitable driving connection from the embossing press drive such as is disclosed in the above noted copending application Serial No. 293,820, filed June 16, 1952.

The mounting bracket 20 is further arranged to carry a color pan 24 and a two-high stack of transfer rolls 26 and 28 forming transfer means for supplying color continuously to the peripheral surface of the applicator roll 10.

Fig. 2 illustrates further the form and arrangement of the applicator roll 10 by representing in perspective the effect on the fabric web W as it travels between the embossing roll 14 and impression roll 16, and then around the peripheral surface of the impression roll 16 past the applicator roll 10 to be taken off as the embossed and design colored web W'. In Fig. 2, and in Fig. 3, too, the form and effect of the intaglio design elements, as at 30, is also illustrated.

The color applicator roll 10 employed according to the present invention is of the type having a covering of resilient material thereon (e. g., a rubber covering), and the intaglio design elements 30 constitute depressions in the peripheral surface of this covering at which the color supplied by the transfer rolls 26 and 28 fails to transfer, leaving the remaining peripheral surface of the applicator roll 10 (exclusive of intaglio design elements 30) as the active color applying surface so that the form of the design elements 30 appears on the processed fabric web W' outlined by the surrounding color applied by applicator roll 10.

The resulting design effect is indicated in Fig. 4 in which a fragment of the processed fabric web W' is shown including the full effect of one of the intaglio design elements 30, the narrow cross lining indicating the raised embossing applied overall to the fabric web W at the nip of the embossing roll 14 and the impression roll 16, and the dark portions of this cross lining indicating the surrounding outline of background color applied by the peripheral surface of the applicator roll 10 at the raised face of the embossed web W'. Alternatively, the background color might be inlaid on the embossed web W' as disclosed in copending application Serial No. 376,712 filed August 26, 1953; or similar design effects might be applied on either one or both sides of a smooth fabric web in the manner disclosed in copending application Serial No. 376,704, filed August 26, 1953.

This invention has been described in detail above for purposes of illustration only, and is not intended to be limited by this description or otherwise except as defined in the appended claim.

I claim:

Apparatus for design coloring of embossed fabric webs, said apparatus comprising an engraved embossing roll, an opposed impression roll forming a backing surface for the fabric web after said web has been embossed, a color

applicator roll arranged in opposed relation to said backing surface for applying color to said embossed fabric web while supported on said backing surface, said applicator roll being covered with a resilient material and having a smooth peripheral surface except for intaglio design elements formed by depressions in the peripheral surface of said resilient material, and means for transferring color to the peripheral surface of said applicator roll exclusive of said intaglio design elements whereby the form of the design elements appears on the fabric web outlined by the surrounding color applied by the applicator roll.
